UNITED STATES PATENT OFFICE.

ARTHUR A. MCRAE, OF ATTLEBOROUGH, MASSACHUSETTS.

DESIGN FOR A BADGE.

SPECIFICATION forming part of Design No. 29,754, dated December 6, 1898.

Application filed November 14, 1898. Serial No. 696,468. Term of patent 3½ years.

To all whom it may concern:

Be it known that I, ARTHUR A. MCRAE, of Attleborough, in the county of Bristol and State of Massachusetts, have invented and produced a new and original Design for a Badge or Similar Article, of which the following is a specification, reference being had to the accompanying drawings, forming part thereof.

Figure 1 is a front view of a badge, showing my design. Fig. 2 is a vertical sectional view of my newly-designed badge. Fig. 3 is a top view of the same.

The leading features of my design consist in the outline and configuration of a box presenting to the eye the appearance of the head of a sledge-hammer projecting from a flat back and a convex tapering stem extending from the head of the badge, presenting to the eye the appearance of a haft or handle projecting from the hammer-head.

In the drawings, *a* indicates the back-plate or surface of the head of the badge; *b*, the

raised surface extending outward from the back-plate *a* and having the inclined sides *b' b'*, the tapering surface *b²*, and the beveled edges *c c*. The back-plate *a* extends at *a'* beyond the raised surface *b* to break the vertical edge of this end of the head of the badge. The convex tapering stem *d* extends at right angle from the head of the badge, the whole presenting to the eye of the ordinary observer the appearance of a sledge-hammer and to the close observer the appearance of half of a sledge-hammer projecting from a flat back.

Having thus described my invention, what I claim as new, and desire to secure by Letters Patent, is—

The design for a badge or similar article herein shown and described.

In witness whereof I have hereunto set my hand.

ARTHUR A. MCRAE.
